(57) **CLAIM**

The ornamental design for a coordinate input device, as shown and described.

DESCRIPTION

FIG. 1 is a front elevation view of a coordinate input device showing our new design;

FIG. 2 is a rear elevation view thereof;

FIG. 3 is a left side elevation view thereof;

FIG. 4 is a right side elevation view thereof;

FIG. 5 is a top plan view thereof, wherein the bottom plan view is the same as the top plan view;

FIG. 6 is a top front left isometric view thereof;

FIG. 7 is a close up view of a portion defined by A-A and B-B of FIG. 6;

FIG. 8 is a front elevation view of a coordinate input device showing a variant of the design;

FIG. 9 is a rear elevation view thereof;

FIG. 10 is a left side elevation view thereof;

FIG. 11 is a right side elevation view thereof;

FIG. 12 is a top plan view thereof, wherein the bottom plan view is the same as the top plan view;

FIG. 13 is a top front left isometric view thereof; and,

FIG. 14 is a close up view of a portion defined by A-A and B-B of FIG. 13.

The broken lines shown in the figures that are immediately adjacent to the shaded areas and define unshaded regions, represent the bounds of the claim; the broken lines form no part of the claimed design.
